(57) **CLAIM**

The ornamental design for a drip edge, as shown and described.

DESCRIPTION

FIG. 1 is a perspective view of a drip edge, showing my new design;

FIG. 2 is an end elevational view; and,

FIG. 3 is a front elevational view thereof.

The claimed design is fragmented on one end indicating that the length of the drip edge is indeterminate.

1 Claim, 1 Drawing Sheet

FIG. 3
